UNITED STATES PATENT OFFICE

2,585,415

REVERSIBLE CUSHION DEVICE

William Alfred Toms, High Wycombe, England

Application June 21, 1949, Serial No. 100,330
In Great Britain March 31, 1948

5 Claims. (Cl. 155—179A)

1

This invention relates to cushion devices and other articles of the same character, such as seat cushions for easy chairs or settees, mattresses for bedsteads, and the like.

The invention has for its main object to provide an improved cushion device of this character composed of sponge rubber, latex foam or other forms of cellular rubber, and enabling free ventilation of air through the interior of the device, the air being circulated by the natural movements of the person sitting or resting upon the cushion device; it is well known that cellular rubber, when in sheet form, is sufficiently porous or permeable for air or perspiration to pass very slowly through the rubber material, but this does not allow for free circulation of air, as is desirable for the upper surface of a seat-cushion or mattress.

A further object of the invention is to provide an improved cushion device composed of cellular rubber material, and reversible in use, like an ordinary cushion or mattress constructed of fibrous material; hitherto, rubber cushions and mattresses have been made with cell-like cavities on the undersurface, or cross-partitioned by dependent walls or webs, which permit access of air from below, but such devices are evidently not reversible.

Another object of the invention is to provide an improved reversible cushion or mattress consisting of two separate surface sheets of cellular rubber material, spaced apart by an interior assembly of coiled upholstery springs, the whole being enclosed in an outer casting with ventilating holes or eyelets around the sides, so that air can circulate freely through the interior and beneath the upper sheet, in whichever position the cushion or mattress has been laid.

Other objects and advantages of the invention will hereinafter appear from the following description given with reference to the accompanying drawings, in which:

Fig. 1 is a perspective view of a bed-mattress embodying one corner of the mattress being torn open to show inner parts.

Fig. 2 is a perspective view, on a larger scale, of one corner of the improved mattress in the preferred form of construction.

Fig. 3 is a vertical section of one side edge, showing additional fastening means for the interior spring assembly.

Fig. 4 is a perspective view of a detail, taken in the middle of the mattress, showing an alternative method of connecting the rubber sheets to the spring assembly.

2

Fig. 5 shows another embodiment, being a vertical section of one side edge of the mattress, and

Fig. 6 is a part perspective view of a border portion of the casing employed in this embodiment.

Referring to Fig. 1, the mattress comprises an outer casing with top and bottom covers 11, two similar surface sheets or layers 12 of sponge rubber, the upper and lower sheets or layers being spaced apart by an interior composed of an assembly of upholstery springs 13 such as employed for ordinary spring mattresses, a large number of these open-type upholstery springs 13 being joined together by helical wire springs 14, arranged transversely of the mattress and around its edges. As seen in Fig. 2, the end coils 15 of the main springs 13 are threaded through the wire coils 14; only one row of springs 13 has been shown in this figure, the position of another row being indicated by the bottom coils 15 in chain lines. The sponge rubber sheets 12 are of slightly larger area than the spring assembly 13—15 upon which they are laid, so as to overlap it at the edges, both sheets being similarly arranged so that the mattress is reversible.

The edges of the rubber sheets are molded or otherwise provided with flaps or flanges 16 to form channels 17, running all the way round each sheet; these channels 17 partly enclose the end coils 15 at the edges of the spring assembly, suitable protection such as sheets of white cotton felt or canvas 18, or cushioning pads of felt or other material being interposed between the spring assembly and the main surfaces of the two rubber sheets 12 so as to prevent the coils of the individual springs from cutting into the rubber. The casing 11, which is fitted over the whole, has its sides or border 19 provided with ventilating eyelets 20 so that air can circulate freely into and out of the interior, being drawn in and blown out by the movements of the sleeper, as in any normal spring-interior mattress; it will however be appreciated that no dust will be produced inside the rubber-spring mattress, as happens in the case of those constructed of fibrous materials, so that the ventilation takes place freely without discharge of dust into the room.

Fig. 6 shows the flanged edges 16 of the rubber sheets 12 are shown in Fig. 2 as connected together by pre-formed border strips 21, forming part of the mattress casing and attached to the sheets 12 by rubber solution or like adhesive; the borders 21 thus consist of double thicknesses of textile ma-

terial 19, 21, sewn together. The inner thickness 21 will have its top and bottom edges attached by adhesive to the respective rubber sheets 12, preferably by turning its edges 22 to overlap parts of the upper and lower faces of these sheets; the outer thickness 18 will finally be sewn to the top and bottom of the case 11 with taped seams 23. The inturned flanges or flaps 16 of the rubber sheets may be molded or punched with holes 24, as shown in Fig. 3, through which fastening means such as cords 25 may be passed for attachment to the top and bottom coils 15 of the springs 13 and/or to any convenient points of the connecting wire springs 14 extending around the mattress; these attachments will serve to anchor the upper and lower rubber sheets 12 to the spring assembly, and to facilitate sliding the whole into the outer casing in readiness for sewing up the taped seams 23.

In order to overcome the possibility of the rubber sheets flapping up and down, or sagging by their own weight when the mattress is being turned, each sheet 12 may be provided with tabs 26 through which cords 27 or other tensile connections can be threaded in the course of construction, these connections passing through the interior spring assembly and thus joining the two rubber sheets 12 together. The tabs 26 may be made of rubber or other suitable material, molded or secured upon the adjacent faces of the rubber sheets, for example to the number of six upon each sheet; Fig. 2 shows a single tab 26 upon the lower sheet, the connection 27 extending up inside the spring 13 to another tab 26 on the inside of the upper sheet, this upper tab being concealed from view.

The side flanges 16 may also be fitted with strips 28 of rubberized fabric or the like, stuck thereon by adhesive or vulcanized in place, these strips having lateral flaps 29 which are affixed to the adjacent surface of the rubber sheets 12.

As an alternative method of connecting the rubber sheets to the spring assembly, Fig. 4 shows one sheet 12 molded with a small channel 30 upon its outward face, with suitably spaced holes 31 passing right through the bottom of the channel; by passing cords 32 through convenient holes 31, looping them over or under the end coils 15 of the springs, laying the intermediate lengths of cord neatly in the channel, and knotting off the ends of the cord close to their last holes, the springs 13 will be connected to the rubber sheet 12, the other sheet being connected in a similar manner to the opposite ends of the springs 13. The knots and thickness of the cords 32 will be left in the channels 30 and they will thus not be felt by a person resting on the mattress. Again, similar channels 30 or countersunk holes can be used to accommodate tufts of the usual kind, with connecting cords passing between the tufts of the upper and lower sheets 12, through the interior spring assembly.

In another method of construction, as illustrated in Fig. 5, the reversible mattress has the rubber sheets 12 connected to the interior spring assembly 13-15 by means of the border portion 19 of the casing, the border 19 (shown separately in Fig. 6) being provided with four horizontal flaps 33-36 for this purpose; two of these flaps 34, 35, are sewn or otherwise affixed to the top and bottom of the spring assembly, of which only one spring 13 is shown in Fig. 5, the extreme upper and lowermost flaps 33, 36 being reserved for fastening the rubber sheets or layers 12. After the two flaps 34, 35 have been affixed to

the spring assembly, the exposed face of the upper flap 34 is coated with a suitable adhesive and the top rubber sheet 12 laid thereon; the uppermost flap 33 is similarly stuck down upon the top rubber sheet, and the top cover or lid 11 is then fixed to the border 19 at the seam 23 by tape sewn on by machine. The mattress is completed by sticking on the other rubber sheet 12 between the lower flaps 35, 36, and sewing on the bottom cover 11 in a similar manner, these operations being more conveniently performed after inversion of the spring assembly with the top sheet 12 attached thereto.

The sponge rubber sheets or layers 12 employed may be made in a single thickness or in two or more thicknesses, of the same or of different degrees of softness; two or more thicknesses may be bonded together on fabric which leaves flaps protruding beyond the edges to form a simple means of attachment of the spring assembly, for example by sewing, the whole being then slid into an outer case or cover.

Instead of open-type springs 13, there may be used encased springs fitted into pockets made of fabric and joined together by stitching or clipping in the well known manner.

The protective material 18, instead of being cotton felt or canvas as indicated above, may consist for example of natural or synthetic rubber, of any desired degree of hardness, stuck to the surfaces of the sponge rubber sheets 12.

The invention may evidently be applied to other articles of the same character, such as cushions for easy chairs or settees, box spring mattresses and the like.

By the term "cellular rubber" as employed in the appended claims, there is to be understood any form of natural or synthetic rubber having air-cells enclosed in the rubber material, for example in the forms known as sponge rubber and latex foam, the particular form of cellular rubber used in making the improved cushion or mattress being such as the judgment of the manufacturer may dictate.

What I claim is:

1. A reversible cushion device of the character set forth, comprising two similar sheets of cellular rubber material, an assembly of coiled upholstery springs interposed between said sheets to space them apart, inturned flanges molded integrally along the edges of said sheets, marginal portions of said spring assembly being engaged between said flanges and edges of said sheets, and an outer casing enclosing said sheets and spring assembly, the sides of said casing being apertured for circulation of air between said sheets.

2. A reversible cushion device of the character set forth, comprising two similar sheets of cellular rubber material, a spring assembly interposed between said sheets to space them apart, said assembly including vertical coiled springs spaced over the area of said sheets and horizontal wire coils extending along the edges of said assembly, said wire coils being threaded upon the ends of aligned vertical springs, inturned flanges molded integrally along the edges of said sheets, one of said horizontal wire coils being engaged between each of said inturned flanges and the adjacent edge of the respective sheet, and an outer casing enclosing said sheets and spring assembly, the sides of said casing being apertured for circulation of air between said sheets.

3. A reversible cushion device of the character set forth, comprising two similar sheets of cel-

lular rubber material, an assembly of coiled springs interposed between said sheets to space them apart, protective material provided between said sheets and the springs of said assembly, said sheets having pre-formed peripheral channels opening inwardly, the end coils of said springs adjacent to the peripheries of said sheets being partly enclosed in their peripheral channels, and an outer casing enclosing said sheets and assembly, the sides of said casing being apertured for circulation of air between said sheets.

4. A reversible cushion device of the character set forth, comprising two similar sheets of cellular rubber material, layers of protective material applied to adjacent faces of said sheets, an assembly of coiled upholstery springs interposed between the protective layers of the respective sheets, said spring assembly spacing said sheets and layers apart over their entire area, inturned flanges along the edges of said sheets, said spring assembly being engaged between said flanges and edges of said sheets, and an outer casing enclosing said sheets and spring assembly, the sides of said casing being apertured for circulation of air between said sheets.

10

25

5. As a new article of manufacture, a rectangular sheet of cellular rubber material molded integrally with flanges along the four sides of said sheet, said flanges being inturned and leaving between their edges and the adjacent edges of said sheet a series of open channels running all the way around said sheet.
